UNITED STATES PATENT OFFICE.

LEVI E. FLINT, OF ASHBY, MASSACHUSETTS.

METHOD OF MAKING ELONGATED TUBS.

SPECIFICATION forming part of Letters Patent No. 426,720, dated April 29, 1890.

Application filed August 17, 1889. Serial No. 321,119. (No model.)

To all whom it may concern:

Be it known that I, LEVI E. FLINT, of Ashby, in the county of Middlesex and State of Massachusetts, have invented a new and Improved 5 Method of Making Elongated Tubs, of which the following is a full, clear, and exact description.

This invention, which relates to the manufacture of elongated tubs and other like vessels suitable either for dry or wet use, and including bathing-tubs, wash-tubs, and casket bodies or foundations, consists in a novel 10 method of making such elongated tubs or vessels, substantially as hereinafter described, and pointed out in the claim, and whereby not only economy, but other advantages are secured.

Reference is to be had to the accompanying drawings, forming a part of this specification, in which similar letters of reference indicate corresponding parts in all the figures.

Figure 1 represents a side view of an ordinary round tub, from which the ends of the elongated tub are made. Fig. 2 is a plan view 25 of said round tub when cut through or divided in the axial line of it. Fig. 3 is a view in perspective of an elongated tub made in accordance with my improved method, and Fig. 4 is an under side plan view of the completed tub.

To make an elongated tub or vessel—that is, an oblong tub or vessel having rounded ends, such as shown, for instance, in Fig. 3 of the drawings—I first turn or make in the 35 lathe, as usual, a round tub—such as shown in Fig. 1—and afterward cut the same through the middle diametrically, thereby forming separate tub-halves A A. These half-round tub-sections I then use to form the ends of 40 the elongated tub shown in Fig. 3, and join to or insert between them sides B B and a bottom C of any desired length and of a depth

or width, respectively, corresponding to the depth and diameter of the tub-sections A A, and put on bands or hoops b b, to hold the 45 whole in place; also, to stiffen and strengthen the tub laterally, I apply one or more stays or fastening-clamps to the bottom of the tub, as best shown in Fig. 4, consisting of a rod c, passing through the chines, through or engaging the lower hoop b, and across the bottom of the tub. As shown, the stay passes through the lower hoop and has its ends headed down thereon.

The tub as thus constructed may be used 55 as a bathing-tub, or as a tub suitable for either wet or dry use, or as a body or foundation for a casket, and with its turned ends and smooth or even surfaces it may be readily covered when required to use it as a casket body or 60 foundation. It will also have great strength, and when used as a wash-tub it provides for a wringer being allowed to remain on one end of it while washing and of a wash-board being used at the other end without placing the 65 clothes under the board. When such a tub, too, is not in use, it may be stood on end without taking any more floor-room than a round tub does.

Having thus described my invention, what 70 I claim as new, and desire to secure by Letters Patent, is—

The method herein described of making elongated tubs, which consists in first turning a round tub, then dividing said tub through 75 its middle diametrically, and then uniting the half-round tub-sections thus produced with an interposed bottom and sides of any desired length and securing the whole together, as set forth.

LEVI E. FLINT.
